(57) **CLAIM**

The ornamental design for an LED luminaire, as shown and described.

DESCRIPTION

FIG. 1 is a lower perspective view of the LED luminaire of the present invention;

FIG. 2 is a bottom view of the design of the present invention;

FIG. 3 is a left side view of the design of the present invention;

FIG. 4 is a right side view of the design of the present invention;

FIG. 5 is a front view of the design of the present invention; and,

FIG. 6 is a rear view of the design of the present invention.

The broken lines showing environmental structure are for illustrative purposes only and form no part of the claimed design.
